UNITED STATES PATENT OFFICE.

THEODORE J. SHONLEY, OF LEAVENWORTH, KANSAS.

INCANDESCENT LAMP.

1,197,555.

Specification of Letters Patent. Patented Sept. 5, 1916.

Application filed December 15, 1914. Serial No. 377,331.

To all whom it may concern:

Be it known that I, THEODORE J. SHONLEY, a citizen of the United States, and a resident of Leavenworth, in the county of 5 Leavenworth and State of Kansas, have invented an Improvement in Incandescent Lamps, of which the following is a specification.

An object of my invention is to provide 10 an incandescent lamp which gives a light of such whiteness and quality that the light may be used for matching colors, where the ordinary electric light cannot so be used.

In the drawings accompanying this specification and forming a part thereof, the preferable form of my invention is illustrated, in which:—

Figure 1 is a view in perspective of my novel lamp. Fig. 2 is a sectional view taken 20 on the line 2—2 of Fig. 1.

Referring to the drawings in which similar reference numerals designate corresponding parts throughout the several views, the lamp includes the usual base 3 and exhausted 25 bulb 4.

The tube 5 which carries the lead-in wires 6 and 7 is supported by the base 3 into which the upper supporting arms 8 are affixed. The insulated post or standard 9 is carried 30 by the tube 5 and supports the lower filament carrying arms 10. The filament carrying arms 8 and 10 are insulated one from the other and include the hooked terminal ends 11 around which the filament extends as is 35 the usual and approved construction.

The filament 12 which is supported by the arms 8 and 10 is formed of a plurality of discontinuous sections 13—14—15, three being illustrated in the present drawings, 40 but it will be readily understood that this number may be varied if desired.

The filament section 13 is in electrical connection with the lead-in 6 and has its opposite discontinuous end 16 rigidly affixed and held stationary by one of the upper filament supporting arms 8. The adjacent filament section 14 is provided with the free bendable end 17 resting upon the stationary end 16 thereof with which it effects a sliding electrical connection. Thus the length 50 of the active portions of the filaments 14 will depend upon the position of the free end 17 and the distance or length thereof which overlaps the stationary end 16 of the adjacent filament. The free end 17 is provided 55 with the spaced stops 18 arranged upon opposite sides of the point of contact between the filament sections and limit the relative sliding motion therebetween. The remote free end 19 of the filament section 14 is 60 similarly arranged and effects a sliding electric connection with the filament section 15, which latter is in electric connection with the lead-in wire 7.

An incandescent lamp constructed as described provides an efficient means for matching colors owing to its peculiar whiteness.

Having thus fully described my invention what I claim is:—

An incandescent lamp having sectional filaments, including two end filaments and a central filament having projecting ends engaging and extending beyond the end filaments.

THEODORE J. SHONLEY.
